UNITED STATES PATENT OFFICE.

ALDEN B. STARR AND ARTHUR E. MEINKE, OF CLEVELAND, OHIO, ASSIGNORS BY DIRECT AND MESNE ASSIGNMENTS, TO SINGLE SERVICE PACKAGE CORPORATION OF AMERICA, A CORPORATION OF NEW JERSEY.

RECEPTACLE.

No. 921,479.

Specification of Letters Patent. Patented May 11, 1909.

Application filed February 24, 1908. Serial No. 417,239.

To all whom it may concern:

Be it known that we, ALDEN B. STARR and ARTHUR E. MEINKE, citizens of the United States, residing at Cleveland, in the county of Cuyahoga and State of Ohio, have invented certain new and useful Improvements in Receptacles, of which the following is a specification.

This invention relates generally to receptacles and particularly to that class wherein the device in its entirety is made up of paper and then coated with a water proofing material such as paraffin.

More specifically the invention is designed as an improvement in paper milk bottles and relates particularly to the construction about the neck and about the bottom wherein the cap is more effectually received and held in place in the mouth of the bottle while the bottom is more firmly secured to the vessel and permits the receptacle to rest squarely and flatly upon its bottom.

The invention may be further briefly summarized as consisting in the construction hereinafter set forth in the following description, drawings and claims.

Referring to the drawings Figure 1 is a side elevation; Fig. 2 is a vertical section; Fig. 3 is a plan of the reinforcing strip to be applied to the neck of the bottle; Fig. 4 is a detail view showing the manner in which the bottom is secured to the body portion of the bottle and Fig. 5 is a detailed view in section of one side of the neck setting forth the reinforcement.

In carrying out our invention any particular form of paper receptacle may be employed provided it has the necessary characteristics; but we have shown one form in the drawings which meets the requirements with great efficiency and in such embodiment 1 represents the body portion which is preferably conical in form, as shown, and has at its upper edge an inwardly projecting flange 2 forming a portion of the seat upon which the cap 2' rests. At its lower edge it is first flanged outwardly to form the flange portion 3 which is adapted to be less in diameter than the diameter of a bottom 4 which is formed with a turned-up edge 4' so that the body portion may set nicely therein and is secured to this body portion by crimping its edge over the edge 3 as shown in Fig. 4 and then turning both parts up against the side of

the body portion 1 as shown in full lines in Fig. 2 thus forming a double seam. Glue is 55 worked into this double seam and serves to hold the parts together.

The reinforcement of the neck is brought about by winding upon the neck portion of the body portion a plurality of circular bands 60 which are preferably formed from one strip as shown in Fig. 3. This reinforcing band strip comprises a relatively narrow portion 5 adapted to wrap around the neck of the bottle so that its edge when in place is flush 65 with the upper face of the flange 2 thereby forming a broad seat for the cap 2'; a relatively broad portion 6 adapted to wrap around the neck of the bottle and around the band portion 5 and further to project above 70 the upper edge of the band 5 and flange 2 to form a cylindrical mouth for receiving the cap as it rests on the seat, and a still broader band 7 adapted to extend entirely around the neck and outside of the band 6 to reinforce 75 the same. This strip is preferably applied by winding it upon the neck and is held in place by means of glue.

It will be seen from the foregoing description that a paper vessel of great efficiency is 80 provided wherein the bottle will rest flat upon the crate wires whereby the weight of the liquid is taken off from the binding edge and a neck structure is produced wherein the cap may rest firmly upon the upper edge of 85 the body portion, thus preventing it from being pushed into the bottle, and the neck structure is reinforced in a manner such that it may not be broken down easily. It is also quite obvious that by this construction only 90 a small portion of the glued joints are exposed to the action of the milk which would tend to loosen them.

Having described our invention, we claim:

1. As an article of manufacture, a paper 95 milk bottle comprising a body portion, a neck portion, reinforcing means surrounding the neck portion and having a portion substantially flush with the upper end thereof, and coöperating therewith to form a cap 100 seat, and a portion extending above the same and forming a cap retainer.

2. In a paper milk bottle, a body portion, a neck portion having its upper edge bent laterally forming a flange, reinforcing means 105 surrounding the neck portion, part of said

reinforcing means extending substantially to the top of the neck portion and coöperating with said flange in forming a cap seat, and part of said reinforcing means extending 5 above the neck portion so as to form a cap retainer.

3. As an article of manufacture, a receptacle comprising a body portion and a reinforcing strip to be wound about the neck and 10 consisting of a relatively narrow portion adapted when applied to form with the upper edge of the body portion a stopper cap seat, and a broader portion adapted to extend above the seat and down onto the neck 15 of the receptacle whereby a retaining portion for the cap is formed above said cap seat and a reinforcement is supplied to the neck.

4. As an article of manufacture, a paper receptacle comprising a body portion having 20 an inwardly projecting flange at its upper edge and a strip wound about the neck of said receptacle and having a portion so ar-

ranged that its edge is flushed with the upper face of said flange thereby forming a stopper cap seat and another portion adapted to extend above said seat and form a projection for retaining a cap upon said seat. 25

5. As an article of manufacture, a paper bottle comprising a body portion and a neck portion having its upper edge projecting inwardly and forming an annular flange, a reinforcing member extending around the neck portion and having a portion flush with said flange and forming with the same a cap seat and a portion extending above the flange and 35 forming a cap retainer.

In testimony whereof we affix our signatures in presence of two witnesses.

ALDEN B. STARR.
ARTHUR E. MEINKE.
